Charles D. Miller Attn:

UNITED STATES PATENT OFFICE

130,672

DESIGN FOR A LIPSTICK HOLDER UNIT

Richard C. Jones, New York, N. Y., assignor to Lucien Lelong, Inc., Chicago, Ill., a corporation of Illinois

Application September 22, 1941, Serial No. 103,448

Term of patent 14 years

To all whom it may concern:

Be it known that I, Richard C. Jones, a citizen of the United States and a resident of the city of New York, in the county of New York, State of New York, have invented a new, original, and ornamental Design for a Lipstick Holder Unit, of which the following is a specification, reference being had to the accompanying drawing, forming a part thereof.

On the drawing:

I claim:

The ornamental design for a lipstick holder unit, as shown.

RICHARD C. JONES,
